Primary Examiner — Eric L Goodman*Assistant Examiner* — Lee D. Starr(74) *Attorney, Agent, or Firm* — Mei & Mark LLP(57) **CLAIM**

The ornamental design for a face mask, as shown and described.

DESCRIPTION

FIG. 1 is a front view of a face mask showing a first embodiment of my new design;

FIG. 2 is a back view thereof;

FIG. 3 is a top view thereof;

FIG. 4 is a bottom view thereof;

FIG. 5 is a right side view thereof;

FIG. 6 is a left side view thereof;

FIG. 7 is a front view of a face mask showing a second embodiment of my new design;

FIG. 8 is a front view of a face mask showing a third embodiment of my new design; and,

FIG. 9 is a front view of a face mask showing a fourth embodiment of my new design.

The broken lines in the drawings depict portions of the face mask that form no part of the claimed design.

1 Claim, 9 Drawing Sheets(56)
